UNITED STATES PATENT OFFICE

ALEXANDER F. C. SCHNOOR, OF LOS ANGELES, CALIFORNIA

ADVERTISING SYSTEM AND APPARATUS

Application filed July 28, 1927. Serial No. 209,148.

This invention relates in general to an advertising system and apparatus for carrying out the system and more particularly to an advertising system for use in market 5 places and apparatus that is particularly adapted to the conditions characteristic of such market places.

An important object of the invention is to provide an advertising system which includes sign racks located in various market places or merchandising establishments, such as grocery, hardware, and drug stores, and hotels or the like, so that consumers of manufactured or other products may be reminded 10 or advised thereof at the opportune moment, or at the time they are actually ready to purchase such products. In accordance with my system the consumer is not only reminded of present needs, but is reminded of 15 an article at the time that a purchase of such an article is both possible and likely, and does not have the usual opportunity of forgetting the thoughts or reminders conveyed to him by similar signs or devices that are remotely 20 located from places where such articles may be obtained.

Another important object of the invention is to provide such a system that provides the merchant in whose establishment the system 25 is installed with a complete series of signs conveying to the consumer the scope of the various lines of merchandise stocked by the merchant, so that his articles are not only continuously advertised but special 30 sales may be advertised by him, by the mere addition to the holding device of a card mentioning the period of the sale and the sale price of the article.

Another important object of the invention 35 is to provide the merchant with means for regular and continuous advertising of a manufacturers products thereby materially increasing the sales of both merchant and manufacturers, also to make it unnecessary 40 for a merchant to have many and costly signs prepared to advise the public of periodic sales.

Another important object of the invention 45 is to provide an apparatus for supporting sign cards in market places that is simple in

construction, substantially rigid, and efficient in operation.

Another important object of the invention is to provide a means for illuminating sign 55 cards, display racks and sign plates in a novel and efficient manner.

Another important object of the invention is to provide a sign rack that is formed of a sign plate upon which the merchant may write, print or otherwise indicate the articles 60 advertised or on sale for that particular day or period, racks extending from the sign plate that are formed of simple brackets attached to the shelving or the like of the market place and card holding plates of simple 65 construction that are arranged to have interlocking engagement with the brackets for supporting the cards thereon.

Numerous other objects and advantages of the invention will be apparent as it is better 70 understood from the following description, which, taken in connection with the accompanying drawings, discloses a preferred embodiment thereof.

Referring to the drawings:—

Figure 1 is a cross sectional view of a portion 75 of a market place showing a sign rack forming a part of my system and embodying my invention.

Fig. 2 is a section taken substantially on line 2—2 in Fig. 1.

Fig. 3 is a section taken substantially on line 3—3 in Fig. 1.

Fig. 4 is a section taken substantially on line 4—4 in Fig. 3.

Fig. 5 is a section taken substantially on line 5—5 in Fig. 1, and Figure 6 is a perspective view showing the several interchangeable parts for making up the sign racks in their relative positions.

To illustrate my invention, I have shown a portion of the interior of a market place, which may be for illustration the interior of a drug store or grocery store and while the apparatus of my system may be arranged in 95 any suitable location or position in such market place or establishment, I have shown my apparatus mounted along the top of a support 11 which may be a shelf rack as shown, a counter or other suitable furniture, 100

the support 11 in the present instance being positioned against a wall 12 in the market place and extending to the usual height which provides a space above the shelf rack at least 5 two feet in height and extending the length of the rack, thus providing a suitable space for the various apparatus of my system.

The apparatus shown in the present instance includes a sign plate 13 and two laterally extending card holding wings 14, the sign plate 13 is preferably a plate upon which the proprietor or merchant may write or print characters setting forth the articles and the price thereof upon which special sales are being 10 conducted for pre-determined periods and may be illuminated upon occasion in any suitable manner. A separate sign plate 15 is 15 preferably mounted adjacent the plate 13 and provided with suitable characters for indicating the period and character of the sale.

In the present instance the sign plate 13 is mounted on a housing 16 (Fig. 3) which is arranged to provide a light chamber 17 and reflecting devices or members 18 and 19, may 20 be arranged in the housing 16 for reflecting light rays from an illuminating means or device 21 located in any suitable position. The lighting device is preferably enclosed in a secondary housing 22 that may be mounted 25 on the housing 16 and constructed and arranged substantially as shown to reflect light rays from the illuminating device 21 into the chamber 17, the sign plate 13 is preferably of substantially transparent material such as 30 frosted glass or the like, upon which the characters may be written or printed so that light rays from the lighting means 21 when projected into the chamber 17 may be reflected by the reflecting devices or members 18 and 35 19 and projected against the sign plate 13 for the illumination thereof.

The path of light rays from the illuminating means 21 to the plate is indicated on the drawings by the dotted lines 23. The secondary sign plate 15 is also preferably of semi or substantially transparent material and may be mounted against a vertical wall 40 24 of the housing 22 substantially as indicated and also illuminated by the lighting means 21 directly or as an incident to the illumination of the sign plate 13.

The sign plate 13 is preferably mounted on the housing 16 so that plate 13 is removable to permit of substitution or alteration upon 55 occasion, this is accomplished in the present instance by mounting the plate 13 on a front panel 25 which may be hinged to the housing 16 by means of a hinge pin 26 extending through a piano hinge formed by a curled 60 portions 27 alternately extending from the panel 25 and a wall 28 of the housing 16. The plate 13 may be supported on the panel 25 in any suitable manner and in the present instance I have shown a pocket or groove 29 65 extending along three sides of the major por-

tion of the edge of the plate 13 and formed by a Z-bar 31 that may be fastened to the panel 25 at spaced points by means of screws 32. A latching device 33 of any suitable type may be provided to engage a flange or lug 34 on the housing 16 to secure the panel 25 in closed position.

In illuminating the plate 13 it is desirable to distribute light rays of substantially uniform intensity from the illuminating device 21 over the area of the plate 13 and while this may be accomplished by positioning the illuminating means at a point somewhat removed from the plate so as to permit direct rays of uniform intensity from the lighting means to strike all points over the area of the plate, the size of the plate is usually too great to permit such an arrangement and to uniformly illuminate the plate 13 in a minimum of space I have arranged a lighting means laterally from or in a position beyond the edge of the plate such as in the housing 22 and provide the reflecting and deflecting devices or members 18 and 19 for distributing the light rays over the plate 13. The reflector or device 18 is preferably formed of a sheet metal plate having a polished or reflecting surface which is corrugated or fluted or otherwise formed to provide a plurality of reflecting surfaces that may extend entirely across 95 the housing 16 as indicated in (Fig. 4). The device 18 may be mounted in the housing 16 in any suitable manner, in the present instance I have shown this device clamped along its edges against flanges 35 on the housing 16 100 by means of angle strips 36 which may be secured to the housing 16 in any suitable manner.

The reflecting device 19 may be any suitable device that is arrangeable on the bottom wall 105 or floor 37 of the housing 16 and may if preferred be formed from a portion of the material of the floor 37. In the present instance I have shown this device formed of sheet metal of substantially V-shape, the uppermost surfaces 38 and 39 being suitably treated 110 to provide reflecting surfaces and arranged in planes crossing each other approximately at right angles and so that the apex of the V-shaped device points toward the illuminating means 21, so that a light ray traveling from the lighting means and striking a reflecting surface of the device 19 will be reflected against the plate 13 direct or against the reflecting device 18 and then against the 115 plate 13 for the illumination thereof.

While the wings or racks 14 may be formed and constructed in any suitable manner, I prefer to form the racks of interchangeable and interlocking mechanical devices or parts and these parts in the present embodiment include card holders 50, cards 51 and 52, brackets 53 and 54, retaining strips 55 and retaining blocks 56, the parts 50 to 56 inclusive form 125 one section of a plain rack or side wing and 130

any number of said sections may be arranged on a suitable support and extended to any suitable length along this support. A secondary wing section 57 which will be later described is provided for each of the above mentioned sections when it is desired to illuminate the cards 51 and 52 and to provide additional advertising space.

The card holder 50 is preferably formed of sheet metal of substantially rectangular form, the body 61 of the holder is or may be slightly curved substantially as shown. The opposite edges of the card holder 50 are preferably curled substantially as indicated to provide holding flanges 62. Each end of the card holder 50 is or may be notched at spaced points as indicated at 63 and 64 to provide a tongue 65. Tongue 65 is bent to one side of the plane of the card holder 50 for embracing the bracket 53 as will be later described. The card 51 may be any suitable sign card and of any suitable material upon which signs may be impressed or supported, the card 51 is substantially the same length 25 as the holder 50 and is somewhat narrower so that it may slide into the grooves provided by the flanges 62 of the holder 50.

The bracket 53 is preferably formed of strip material and bent substantially as indicated to provide a leg 66 having one or more apertures 67 therein to provide a means for securing the bracket 53 to the support 11 and a leg 68 which is formed substantially in accordance with the normal surface of the card holder 50. The leg 68 is provided with spaced notches 69 and the material of the legs at one side of the notch is bent from the plane of the legs substantially as indicated. The spacing of the notches 69 is equal to the spacing 40 of the slots 63 and 64 of the holder 50. The retaining strip 55 may be a strip of any suitable material the length of which is substantially equivalent to the width of the sign card 51.

The bracket 54 is similar to the bracket 53 and may be formed of the same material to provide a leg 71 having apertures 72 therein which are preferably similar to and in alignment with the apertures 67 in the bracket 53. The bracket 54 is also formed to provide a leg 73 having notches 74 adjacent the end thereof. The material of the leg 73 between the notches 74 and the end thereof is preferably curled or bent from the plane of the leg 73 substantially as indicated at 75 and a protuberance 76 is preferably struck up from the surface of the leg 73 adjacent its uppermost end. The retaining plate 56 may be any suitable plate and is preferably formed to an ornamental design and to at least cover the area of the leg 73 of the bracket 54. The plate 56 is preferably apertured as indicated at 77 through which a fastening device such as a screw 78 or the like may extend for threaded engagement in a threaded aperture

79 in the bracket 54. The card 52 may be any indicia bearing or sign card and it is substantially the same length as the card 51.

The brackets 53 are spaced along a support and may be secured thereto as indicated (Fig. 5) by means of bolts 81 or other suitable fastening devices engaging the support 11, the spacing of the brackets is determined by the length of the card holder and is such that a card holder may be positioned between each bracket with the tongues 65 extending back of leg 68 of the bracket 53 and the remainder of the ends of the card holders in front of the leg 68, the tongues 65 are preferably arranged to yieldingly clamp the body of the card holder 50 against the legs 68. The tongues 65 being positioned between two spaced notches 69 and embracing the leg butts against offset portions thereof and when assembled each card holder 50 is interlockingly engaged between two brackets 53. After the card 51 is inserted in any holder the retaining strip 55 is positioned over the joint between each pair of adjacent cards to cover the joint therebetween.

The brackets 54 are preferably positioned beneath each bracket 53 substantially as shown and provide a means for supporting the card or cards 52, these cards rest at their opposite ends on the tip provided by the curved portions 75 of the legs 73 and the slot 74, the retaining plates 56 are then placed over the opposite ends of the cards 52 and the screws 78 are inserted and drawn up to clamp the cards in fixed position.

The secondary wing sections 57 are provided when it is desired to illuminate the sign cards 51 and 52 and to provide an additional sign plate 82. The sections 57 include the plate 82, a holding frame 83 therefor, a hood 84, an illuminating device 85, braces 86 and braces or supporting brackets 87. The sign plate 82 is preferably mounted, removably, in the frame 83, and the frame 83 may be secured to the hood 84 in any suitable manner. The hood 84 is preferably shaped to provide a reflector for the illuminating device 85 as indicated (Fig. 5) and to lap over or back of the card holder 50 when assembled thereto. The braces 86 are preferably narrow strip braces arranged at each end of the unit 57 and the braces 87 are similarly arranged at each end thereof and to embrace the hood or for attachment thereto in any suitable manner. The braces 86 support the lower edge of the frame 83 from the rear of the hood substantially as indicated and the braces 87 are extended from the hood to engage the end of the legs 68 of the brackets 53 for attachment thereto by means of screws 88 or other suitable fastening devices. The length of the secondary wing sections 57 is preferably equal to the space between the brackets 53 and one of such units may be arranged above each of the sec-

tions of the wings 14. The illuminating devices 21 and 85 are preferably incandescent bulbs or similar light. The arrangement of the secondary wing sections is preferably such that the light rays from the illuminating device 85 will be projected through the sign plate 82 and over the surface of the sign cards 51 and 52 substantially as indicated by dotted lines 89 to provide indirect illumination therefor. Sheet metal plates 91 are preferably provided at each end of the wings 14 to close the ends thereof and to aid the appearance which may be of any suitable shape and provided with ornamental designs upon occasion.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. In an advertising apparatus, a card supporting rack comprising, a plurality of spaced brackets constructed and arranged for attachment to a support, and card holding members interlockingly engaging said brackets and supported thereby.

2. In an advertising apparatus the combination of a central character displaying panel, and card supporting wings extending laterally from said panel, said card supporting wings being formed of spaced supporting brackets and card holding devices extending between said brackets and supported thereby.

3. In an advertising apparatus the combination of, a plurality of spaced supporting members, card holding plates extending between and supported by said members, sign cards displayed in said plates, and devices supported by said supporting members, and arranged to provide indirect illumination for the sign cards in said card holding plates.

4. In an advertising apparatus the combination of, a plurality of spaced supporting members, card holding plates extending between and supported by said members, and illuminating devices supported by said supporting members and having a bearing on the card holding plates, said devices being formed to provide a light reflector and for holding transparent sign plates, and provided with illuminating means.

5. A card holding rack, comprising in combination, card holders, and spaced brackets, said brackets being formed of strip material to provide a leg for attachment to a support, and a leg adapted to be embraced by a portion of at least one card holder and having

offset portions for preventing movement of the card holder along said leg.

6. A card holding rack, comprising in combination, card holders, and spaced brackets, said card holders comprising, substantially rectangular sheet metal plates having curled edges adapted to embrace edges of a card and having an offset portion adjacent at least one end adapted to embrace one of said brackets for supporting the card holder thereon.

7. A sign display rack comprising in combination a plurality of spaced substantially L-shaped supporting brackets having offset portions providing stops, and card holding devices adapted to extend between and embrace portions of said brackets and to engage said stops.

8. In an advertising apparatus the combination of, a plurality of spaced supporting members, card holding plates extending between and supported by said members, and illuminating devices supported by said supporting members, said devices being formed to provide a light reflector and for holding transparent sign plates, and provided with illuminating means.

9. In advertising apparatus the combination with a series of display cards of means for displaying said cards, including a centrally disposed attractive unit, and means for individually supporting display cards of the series adjacent said unit for display in conjunction therewith, said means comprising, a plurality of spaced brackets constructed and arranged for attachment to a support, and card holding members interlockingly engaging said brackets and supported thereby.

10. In advertising apparatus the combination with a series of display cards, of means for displaying said cards, including a centrally disposed attractive unit, and means for individually supporting display cards of the series adjacent said unit, for display in conjunction therewith, said means comprising, spaced supporting devices, and card holders arranged to extend between said devices and having interlocking engagement therewith.

11. In advertising apparatus the combination with a series of display cards, of means for displaying said cards including an ornate and conspicuous display unit, and means for supporting display cards of the series adjacent said unit for display in conjunction therewith, said means comprising, a plurality of spaced brackets constructed and arranged for attachment to a support, and card holding members interlockingly engaging said brackets.

12. In advertising apparatus the combination with a series of display cards, of means for displaying said cards including an ornate and conspicuous display unit, and means for supporting display cards of the series adjacent said unit, for display in con-

junction therewith, said means comprising, spaced supporting devices, and card holders secured between said supporting devices.

13. In advertising apparatus the combination with a series of display cards, of means for displaying said cards including an ornate and conspicuous display unit, and means for supporting display cards of the series adjacent said unit, for display in conjunction therewith, said means comprising, spaced support members, card holders attached to said support members, and illuminating means associated therewith.

14. In advertising apparatus the combination with a series of display cards, of means for displaying said cards including an ornate and conspicuous display unit, and means for supporting display cards of the series adjacent said unit, for display in conjunction therewith, said means comprising, spaced support members, card holders attached to said support members, and illuminating means associated therewith, said illuminating means being at least partly concealed and provided with a reflector.

15. In advertising apparatus the combination with a series of display cards, of means for displaying said cards including a centrally disposed display unit, and card holding devices formed of interlocking members extending from said unit for supporting display cards of the series adjacent said unit and for display in conjunction therewith.

16. In advertising apparatus the combination with a series of display cards, of means for displaying said cards, including a centrally disposed attractive unit, and means for individually supporting and displaying the cards of the series adjacent said unit.

17. In advertising apparatus the combination with a series of display cards, of means for displaying said cards including a separate and ornate centrally disposed display unit, and card supporting means arranged to extend from said unit for displaying a plurality of cards of the series adjacent said centrally disposed display unit.
